UNITED STATES PATENT OFFICE.

WILLIAM JAKOB BEISEL, OF BROOKLYN, NEW YORK.

NON-REFILLABLE BOTTLE.

1,241,810.

Specification of Letters Patent.

Patented Oct. 2, 1917.

Application filed April 10, 1916. Serial No. 90,199.

To all whom it may concern:

Be it known that I, WILLIAM J. BEISEL, a citizen of the United States, residing at Brooklyn, Kings county, State of New York, have invented certain new and useful Improvements in Non-Refillable Bottles, of which the following is a specification.

This invention relates to non-refillable bottles of the type disclosed in my prior Patents Nos. 1,079,387; 1,144,286 and 1,144,287. As fully disclosed in those prior patents, I have invented means for preventing a liquid from entering a bottle and have thus produced a bottle which cannot be refilled and the construction by which this is accomplished includes a tapered valve in the neck of the bottle and a weight down within the body of the bottle connected to the valve by a flexible connection. As set forth in my prior patents, it is necessary to have a flexible connection from the weight to some support at the bottom of the bottle and in the construction shown in those cases I made use of a screw plug in the bottom of the bottle for that purpose. This, however, made it necessary to make a hole in the bottom of the bottle. It has been my purpose in the present case to avoid the necessity for making such hole in the bottom of the bottle and to provide simple and convenient means for properly balancing the weight near the bottom of the bottle by means which can be inserted through the neck of the bottle while the mechanism for preventing refilling is being placed in position and which can be removed from the bottle if the mechanism which prevents refilling is removed from the neck. With this object in view my invention consists in what I call locking balance shaft, to which the weight in the bottle is flexibly secured.

The novel features of the invention will be apparent from the following description, taken in connection with the drawings. In the drawings:

Figure 1 is a vertical section of a bottle having my invention applied thereto;

Fig. 2 is a detail perspective view of my automatic locking balance shaft;

Fig. 3 is a detail view of a slightly modified construction; and

Fig. 4 is a cross section on the line 4-4 of Fig. 3.

As shown in the drawing, my invention is applied to a bottle 1 having a short neck section 2 and it will, of course, be made of

glass in the usual and well known way. Within the neck portion 2 there is suspended a cylindrical hollow member 3 supported by the annular flange 4 and provided with the openings 6 to permit the passage of fluid through it. Above the neck portion 2 there is placed the valve seat 10 in which fits the tapered valve 12. A chain or other flexible connection 16 is connected to the lower end of the valve 12 and passes out through the opening 7 in the bottom of the cylinder 3 into the body of the bottle and is there secured to the weight 17, which may be made of glass. The purpose of this weight and its connection to the valve, as pointed out in my prior patents, is to hold the valve closed unless the bottle is in a vertical position with the neck downward. The neck of the bottle includes an upper section 8 above the section 2 and secured thereto by the collar 9. It seems unnecessary in the present case to describe in detail the mechanism in the neck of the bottle to prevent liquid from entering the bottle or in other words to prevent refilling, since that matter is fully set forth in my prior patents above mentioned.

My present invention consists in a frame 20 which extends from the top of the bottle 85 closely adjacent to the inner surface down one side to and across the bottom to the opposite side. This frame or automatic locking balance shaft is preferably made of glass but may, of course, be made of any 90 suitable material. As clearly shown in Fig. 1, this frame has the upper portion 21 turned in to conform to the under surface of the shoulder or top 22 of the bottle and it is extended inward until it reaches the cylindrical member 3. Its inner end is curved on the arc of a circle to fit around the cylinder 3 so as to lock the device in place and it will be observed that the end 21 is wider vertically than the openings 6, so that it will not 100 catch in the openings in the cylinder. This end 21 furthermore has an opening through it in which is inserted a yielding piece of material such as cork 23, which projects beyond the surface of the frame and into 105 contact with the under surface of the top wall of the bottle. The portion of the frame 20 at the bottom of the bottle extends at 24 across the bottle and its end is curved upwardly to a point 25 adjacent the opposite 110 wall of the bottle. A hole is provided in the frame at the bottom and a piece of yield-

ing material, such as cork, 26 is inserted in that hole and projects therefrom against the bottom of the bottle. The end 25 is also provided with a hole 27 in which the cork 28 or other material is secured, projecting out against the side of the bottle. It will be observed that the frame extending in close proximity to the walls of the bottle will be held firmly but yieldingly in position by the various pieces of cork projecting from the frame at intervals and it is preferable to maintain the frame at a slight distance from the walls so that the rigid parts of the frame will not make actual contact with those walls. This is to allow for expansion and contraction and to prevent breaking the frame or bottle.

The frame, as shown, can be inserted through the neck 2 of the bottle before the upper portion 8 and the contents of the neck have been inserted. It will be observed that the lower part of the frame passes across the center line of the bottle at the bottom and thus furnishes a convenient support to which is attached the flexible connection 29 secured to the bottom of the weight 17. That flexible connection passes through or is secured to the frame at 30. In inserting the frame 20 into the bottle, the flexible connection 29 is first secured to it and to the weight 17 and after the frame is within the bottle the cylindrical portion 3 is inserted in the neck and thus locks the frame in position.

Instead of having the frame at its upper end 21, as shown in Fig. 1, extend over and into contact with the cylinder 3, I may modify the construction, making that end shorter, as shown in Fig. 3, and provide a separate extension 31 below the top extending inwardly against the side of the cylinder 3. I still make use of the cork 28, however, to properly support the device from the top of the bottle. Either form of the device is very simple in construction, can be manufactured cheaply and can be placed in position very easily. It furthermore serves the purpose very effectively of supporting and balancing the weight which controls the valve without making it necessary to make any opening in the bottle itself. My supporting shaft can furthermore be removed from the bottle after the bottle is empty and is taken apart so that it may be used again. For that purpose the old corks 23, 26 and 28 may be removed, the device cleaned and sterilized and new corks substituted.

While the shaft for the automatic locking of the valve herein claimed is adapted for use in various forms of bottles it has been designed particularly for use in connection not only with my inventions set forth in my patents above mentioned but also that set forth in my copending application 65,101 filed December 4, 1915. As set forth in said

application the neck of the bottle above the valve includes the two separated sieves 32, 33 to prevent getting anything down through the neck and lodging it beneath the valve.

Having thus described the invention, what is claimed and desired to be secured by Letters Patent is:—

1. In a non-refillable bottle, the combination with a bottle of means in the neck of the bottle for preventing a liquid from entering the bottle including a tapered valve, a weight within the bottle flexibly connected to said valve, a frame of rigid material within said bottle adapted to be withdrawn through the neck, the said frame extending across the bottom and up one side of the bottle to a point adjacent the neck, means for yieldingly but firmly supporting said frame from the bottom and sides of the bottle to hold it in place, and flexible means connecting said weight to the frame at the bottom of the bottle and on substantially the center line thereof. 75 80 85

2. In a non-refillable bottle, the combination with a bottle of means in the neck of the bottle for preventing a liquid from entering the bottle including a tapered valve, a weight within the bottle flexibly connected to said valve, a frame of rigid material within said bottle extending from the neck 90 portion of the bottle in close proximity to the inner surface down one side and across the bottom and provided at intervals with holes, corks in said holes projecting outwardly into contact with the inner surface of said bottle at the bottom and sides to hold said frame yieldingly but firmly in place, and flexible means connecting said weight to said frame at the bottom of the bottle and on substantially the center line of the bottle. 100 105

3. In a non-refillable bottle, the combination with a bottle of means in the neck of the bottle for preventing a liquid from entering the bottle including a tapered valve, a weight within the bottle flexibly connected 110 to said valve, a frame of rigid material within said bottle adapted to be withdrawn through the neck, the said frame having a portion extending across the bottle at the bottom, means co-operating with the inner 115 surface of the bottle for firmly but yieldingly holding said frame in place, and means for flexibly connecting said weight to said portion of the frame extending across the bottom. 120

4. In a non-refillable bottle, the combination with a bottle of means in the neck of the bottle for preventing a liquid from entering the bottle including a tapered valve and a cylindrical portion projecting downwardly into the bottle from the neck, a weight within the bottle flexibly connected to said valve, a frame embodying a shaft of rigid material within said bottle adapted to be withdrawn through the neck, and extend- 125 130

ing from the portion of the bottle immediately below the neck down one side to and across the bottom of the bottle, the said shaft including a portion projecting to and fitting 5 against said cylindrical portion, yielding material secured to and projecting from said frame at intervals into contact with the walls of the bottle to hold it in place, and flexible means connecting said weight to 10 said frame at the bottom.

5. The combination with a bottle of valve mechanism to prevent refilling in the neck thereof embodying a cylindrical portion projecting into the bottle, a shaft within 15 said bottle and adapted to be withdrawn through the neck, the said shaft extending from the top to and across the bottom of the bottle and having a portion engaging

said cylindrical portion, and yielding projections engaging the bottom, side and top 20 of the bottle.

6. In a non-refillable bottle, the combination with a bottle of means in the neck of the bottle for preventing a liquid from entering the bottle including a tapered valve 25 and a cylindrical portion projecting downwardly into the bottle from the neck, a weight within the bottle flexibly connected to said valve, a removable shaft in said bottle separate from said means in the neck 30 securely held against accidental movement by contact with the interior of the bottle, and a flexible connection between said weight and shaft below said weight.

In testimony whereof I affix my signature. 35
WILLIAM JAKOB BEISEL.
